UNITED STATES PATENT OFFICE

155,949

DESIGN FOR A TRAY

Mike M. Wiley and Graham M. Norden,
Nashville, Tenn.

Application May 14, 1948, Serial No. 146,364

Term of patent 14 years

(Cl. D44—10)

To all whom it may concern:

Be it known that we, Mike M. Wiley and Graham M. Norden, citizens of the United States, residing at Nashville, Tennessee, have invented a new, original, and ornamental Design for Tray, of which the following is a specification, reference being had to the accompanying drawing, forming part thereof.

Figure 1 is an elevational view of a tray, showing our new design; and

Figure 2 is a plan view thereof.

We claim:

The ornamental design for a tray, as shown.

MIKE M. WILEY.
GRAHAM M. NORDEN.
